UNITED STATES PATENT OFFICE.

ANSON E. PERRIN, OF CENTRAL FALLS, RHODE ISLAND.

DESIGN FOR MONUMENTS.

Specification forming part of Design No. 7,509, dated June 30, 1874; application filed May 11, 1874.
[Term of Patent 14 years.]

To all whom it may concern:

Be it known that I, ANSON E. PERRIN, of Central Falls, in the county of Providence and State of Rhode Island, have invented a Design for Monuments, of which the following is a specification:

My invention is fully represented in the accompanying drawings, to which reference is made.

A represents a monument of triangular form, so that it presents two angular faces or tablets, *a a*, for the inscription, and a rear side for a like purpose, if desired. The upper end of each tablet may be curved or ornamented in any desirable manner. The upper portion of the monument may be ornamented with a scroll, C, or other similar design, giving it an

ornamental appearance, and affording a surface for a name.

I prefer to make the top ornament in the form of a scroll, as shown; but I do not consider the scroll or top ornament to be an essential element of my design. The monument A rests upon a sub-base, *c*, and a base, *d*.

What I claim as my invention is—

A design for a monument in the form of a triangular prism, in which two faces or tablets and a back are presented for inscription, substantially in the manner above described.

ANSON E. PERRIN.
